Primary Examiner — Anhdao Doan(74) *Attorney, Agent, or Firm* — Meyertons, Hood, Kivlin, Kowert & Goetzel, P.C.; Eric B. Meyertons(57) **CLAIM**

The ornamental design for an x-ray marker, as shown and described.

DESCRIPTION

FIG. 1 is a front perspective view of an x-ray marker.

FIG. 2 is a front view of an x-ray marker.

FIG. 3 is a top side view of an x-ray marker.

FIG. 4 is a right side view of an x-ray marker.

FIG. 5 is a left side view of an x-ray marker.

FIG. 6 is a bottom view of an x-ray marker; and,

FIG. 7 is a rear view of an x-ray marker.

The broken lines in the drawings are for illustrative purposes only and form no part of the claimed design.

1 Claim, 2 Drawing Sheets See application file for complete search history.
